Watson E. Coleman ATTORNEY.

UNITED STATES PATENT OFFICE.

THEODORE D. ANAGNOSTOPOULOS, OF OPELOUSAS, LOUISIANA, ASSIGNEE OF ONE-HALF TO JAMES M. FOX, OF NEW ORLEANS, LOUISIANA.

BOX-LID HOLDER.

1,388,147.

Specification of Letters Patent. Patented Aug. 16, 1921.

Application filed November 22, 1920. Serial No. 425,799.

To all whom it may concern:

Be it known that I, THEODORE D. ANAGNOSTOPOULOS, a citizen of the United States, residing at Opelousas, in the parish of St. Landry and State of Louisiana, have invented certain new and useful Improvements in Box-Lid Holders, of which the following is a specification, reference being had to the accompanying drawings.

10 This invention relates to box lid holders and has for its object to provide a device of this character capable of being readily applied to any hinged box lid without the use of fastening means.

15 Another object is to provide a holder of this character which not only holds the lid in its open position but provides a finger piece by means of which the lid may be readily raised.

20 A still further object of the invention is to provide a holder of this character formed from a single length of resilient material, one end portion of the length being extended back upon said length and adapted to 25 engage the rear portion of the box to maintain the cover in its open position.

25 A still further object of the invention is to provide a holder of this character having one end portion thereof extended back upon 30 the body member of the device and then extended in angular relation thereto to provide connecting means, said rearwardly extended portion not only serving as means to maintain the cover in its open position but 35 as means to absorb any normal amount of pressure which would tend to move the cover toward the rear portion of the box.

With the above and other objects in view, 40 the invention consists in the improved construction and arrangement of parts to be hereinafter more particularly described, fully illustrated and claimed in the accompanying drawings, in which:—

Figure 1 is an end elevation of a box 45 showing the invention applied,

Fig. 2 is a bottom plan view of the holder, Fig. 3 is a side elevation, and

Fig. 4 is a perspective view of a box showing the device used as means for raising the 50 lid of the box.

Referring to the drawings, A designates a box having a hinged cover B. It is difficult, with boxes of this character to not only

open the lid but to maintain the lid in its open position and prevent the same from accidentally closing.

In order to overcome this disadvantage, there is provided a length 5 of material preferably resilient metal having its end portion 6 tapered, the apex of said tapered portion 60 being extended in right angular relation to the length to provide a spur 7. This spur forms one portion of the fastening means for securing the holder to the lid of the box.

The end portion 8 of the length or body 65 member 5 is extended in angular relation to the body member 5 as at 9. The purpose of this is to permit said end portion to extend beneath the rear edge of the cover B and engage the rear wall of the box A, said 70 angular extended portion permitting the lid to be maintained in its open position without inclining the lid to any great extent. The portion 10 of the end portion 8 is then extended back upon the body member to the 75 junction of the angular extended portion with the body member. The last mentioned portion is tapered, and has its extremity 11 extended substantially in right angular relation to said portion 10 and in angular relation to the body member 5. The apex of the extremity 11 is then extended in right angular relation to the extremity 11 to provide a spur 12.

By this novel formation of the end 8 a 85 number of advantages are derived; for instance the spur 12 extends toward the end 6 of the body member to facilitate application of the holder to the lid. At the same time a recess 13 is formed through the co-operation of the spur 12 and the adjacent portion of the body member 5. This recess is intended to receive the hinged edge of the cover B while the portion 10 and the angularly extended portion of the end 8 are disposed in spaced parallel relation to each other so that a spring action results.

In the application of the holder, the same is applied so that the hinged edge of the cover B is disposed within the recess 13, the 100 spur 12 extending through the hinged connection, and frictionally engaging the inner surface of the lid. If the lid is relatively thick the spur may be disposed within the edge. The spur 7, is then forced into the 105 outer surface of the cover. In view of the

resiliency of the holder it is impossible for any normal force to disengage the holder from the lid.

An important feature of this holder is that the angularly extended end portion 8 projects beyond the hinged edge of the cover B and slightly downwardly so that when the cover is raised, the end of the angularly extended portion will engage the rear wall 10 of the box A and hold the lid in its open position. Should any pressure be applied to the lid in its open position which would tend to move the lid toward the rear wall, the portion 11 coöperating with the angularly extended portion of the end 8 will resist the pressure so as to maintain the lid in its open position and at the same time prevent disengagement of the holder from the box.

20 Another important function is performed by the angularly extending end 8 of the body member namely, that of providing a finger piece which permits the lid to be readily opened. This is accomplished by simply 25 pressing on the angularly extended end 8 so as to cause said end to move toward the rear wall of the box. This novel feature is especially advantageous when the holder is used in connection with boxes that are difficult to open, such as cigar boxes. If desired, one of the holders may be placed on the forward portion of the lid as shown in Fig. 4 to provide a finger piece at the forward portion of the box instead of at the 30 rear portion as above described. In this way, one holder serves to hold the lid in its open position while the other is used as means for raising the lid.

From the foregoing it will be readily seen 40 that this invention provides a novel form of box lid holder which may be readily applied to any box using a hinged lid to not only hold the lid in its open position, but to

also provide means whereby the lid may be easily moved to its open position. All of 45 these features are possessed by a device that may be made from a single length of material and which does not require separate fastening means to hold the same in engagement with the box.

50 What I claim is:—

1. A box lid holder consisting of a length of resilient material having a spur formed in one end portion, the opposite end of said body member being extended back upon 55 said body member to provide a stop, the extremity of said end portion being offset and formed into a spur.

2. A box lid holder consisting of a length of resilient material, a spur formed on one 60 end of the body member, said spur extending in right angular relation to the body member, the opposite end portion of said body member being extended in angular 65 relation to the body member, and back upon the body member and then extended at right angles to the body member, said last mentioned right angular portion having a spur formed thereon, said spur extending in spaced parallel relation to the body member 70 and toward the first mentioned end of the body member.

3. A box holder consisting of a length of resilient material having a spur formed on one end portion thereof, the opposite end portion being extended back upon said 75 length, in parallel relation thereto to substantially form a resilient stop, the extremity of the last mentioned end portion being offset and formed into a spur, whereby movement of the body member will cause yieldable movement of the stop upon contact of the stop with the box.

In testimony whereof I hereunto affix my signature.

THEODORE D. ANAGNOSTOPOULOS.
